UNITED STATES PATENT OFFICE.

WILLIAM J. BARGEN, OF WAUKEGAN, ILLINOIS, AND WILLIAM R. BRENNAN, OF MISSOULA, MONTANA.

SEAT-ADJUSTING MEANS.

Original application filed October 27, 1924, Serial No. 746,066. Divided and this application filed August 28, 1925. Serial No. 53,099.

To all whom it may concern:

Be it known that we, WILLIAM J. BARGEN and WILLIAM R. BRENNAN, citizens of the United States, residing at Waukegan, in the county of Lake and State of Illinois, and Missoula, in the county of Missoula and State of Montana, have invented certain new and useful Improvements in Seat-Adjusting Means, of which the following is a specification.

This invention, which is a division of our joint application filed October 27, 1924, Serial Number 746,066, relates to furniture, such as a combined desk and seat for use in school and lecture rooms, but it is to be understood that an article of furniture, in accordance with this invention, can be employed or used for any purposes for which it is found applicable, and the invention has for its primary object to provide, in a manner as hereinafter set forth, an article of furniture with a combined connecting and adjusting means for a seat unit or structure, whereby the latter can be adjusted and secured in adjusted position to afford maximum amount of comfort with respect to the user's arms, feet and legs, and further which will permit of the seat unit or structure being removed from the desk or book body and its supporting means to provide what may be termed a front desk.

A further object of the invention is to provide, in a manner as hereinafter set forth, an article of furniture, such as a combined desk and seat, including a pedestal and seat supporting bracket, and with new and novel means cooperating with the pedestal and bracket for securing the latter in its adjusted position.

Further objects of the invention are to provide, in a manner as hereinafter set forth a combined connecting and adjusting means for a seat unit or structure, and which is simple in its construction and arrangement, strong, durable, compact, thoroughly efficient in its use, conveniently operated to adjust the seat unit or structure and to secure the same in adjusted position, and comparatively inexpensive to manufacture.

With the foregoing and other objects in view, the invention consists of the novel construction, combination and arrangement of parts, as hereinafter more specifically de-

scribed and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a sectional elevation, broken away, of a combined desk and seat showing the adaptation therewith of a combined connecting and adjusting means, in accordance with this invention, for a seat unit or structure.

Figure 2 is a sectional plan.

Figure 3 is a fragmentary view in sectional elevation.

Figure 4 is a fragmentary view in rear elevation of the seat bracket.

Figure 5 is a section on line 5—5, Figure 3.

Figure 6 is a front elevation and Figure 7 a side elevation, partly in section, of the binder or holder member for the seat bracket.

Referring to the drawings in detail, 1 denotes a desk or book box, 2 a vertically adjustable supporting standard therefor, and 3 a pedestal provided with a passage or socket 4 for the reception of the lower end of the standard 2. The pedestal 3 carries clamping elements 5, 6, 7 for the standard 2. The elements 5, 6, 7 are more clearly shown and described in the application aforesaid and are not claimed in this application.

A combined connecting and adjusting means, in accordance with this invention, for a seat unit or structure, comprises the pedestal 1, a seat bracket forming an element of the seat unit or structure, a binder or holder member and a plurality of clamping elements, and said means not only removably connects the seat unit or structure to the pedestal, but also fixedly secures it in adjusted position.

The pedestal 1 is constructed from a hollow casting having a tapered shank 8 and a base 9 provided with openings 10 for the passage of hold fast devices to fixedly secure the base to the floor or other suitable support. The hollow pedestal is constructed in a manner to provide the passage or socket 4 to conform to the shape of the standard 2, as shown of polygonal contour. The front

of the shank 8 is flattened, as at 11, for a substantial portion of its length and with such flattened portion extending from the top edge of the pedestal. The said flattened portion 11, at its lower end, terminates in a forwardly directed shoulder 12. Formed integral with the front of the shank 4 and extending from the top thereof to the shoulder 12, is a pair of lengthwise extending and forwardly directed oppositely disposed spaced flanges 13, 14, and each of which is angle-shaped in cross section, see Figure 2.

The forward portion of each of the flanges is disposed at right angles and extends inwardly with respect to the rear portion thereof, and the latter spaces the former from the shank 8. The forward portion of each flange gradually decreases in thickness from the top of the bottom thereof. The outer face of each forward portion is provided with transverse teeth, as at 15.

The flanges 13 and 14, in connection with the flat portion 11, form the front of the shank 8 with a vertically disposed pocket 15' which is T-shaped or dove-tail in cross section. The pocket 15' extends from the top of the pedestal to the shoulder 12, and is a part of the combined connecting and adjusting means for the seat unit. The teeth of the flanges 13, 14 provide a pair of racks and form elements of the combined connecting and adjusting means for the seat unit.

The supporting bracket for the seat member 16 and seat back 17 is indicated at 18 and is of U-shape contour or of yoke shape. The rear face of the bracket 18, centrally thereof, is formed with a vertically disposed groove 19, of substantial width, and projecting from each side wall of the groove 19, as well as being formed integral therewith and with the bottom of the groove, is a plurality of teeth 20. Each of the teeth 20 is of a length to terminate at a point removed from one side of the vertical median of the bracket 18. A pair of superposed spaced openings 21 is arranged at the vertical median of the bracket 18, and the latter, centrally of its forward face, is formed with a notch 22, which extends from its top edge and terminates in the bottom of the groove 19. The bottom of the notch is rounded. The bottom edge of the bracket 16, centrally thereof, is provided with a notch 23 having rounded side walls. The side walls of the groove 19 are rounded.

The bracket 18 is vertically adjusted on the flange 13 and 14 and when adjusted the teeth 20 engage in the teeth 15. For securing the bracket 16 in adjusted position, the binder or holder member and the pair of clamping elements are employed.

The binder or holder member consists of a vertically disposed rectangular body portion 24 having the corners rounded, as at 25. Formed integral with the forward face of

the body portion 24, is an enlargement 26 which extends throughout said face centrally thereof and is provided with a pair of shoulders 27, 28. Integral with the top of the enlargement as well as projecting forwardly therefrom, is an angle-shaped supporting lug 29. Formed integral with the bottom of the enlargement, projecting forwardly therefrom and at right angles thereto, is a lug 30. The lug 29, when the binder member is in position, within the pocket 15', extends outwardly between the flanges 13, 14, through the notch 22, and overlaps the top edge of the bracket 18. The lug 30 extends outwardly between the flanges 13 and 14 and through the notch 23.

The binder member, centrally thereof, is formed with a pair of spaced openings 31, 32, having threaded walls, and which register with the openings 21 formed in the bracket 18. The groove 19 is of a width to overlap the flanges 13 and 14 when the supporting bracket is mounted in position. The supporting bracket carries the binder member and when said bracket is mounted in position, the body portion 24 of the binder member, as well as an enlargement 26 thereof, is arranged in the pocket formed by the flanges 13, 14. The body portion 24 is positioned between the horizontal legs of the flanges and the flattened portion 11, and the enlargement 26 extends between the horizontal legs of the flanges 13, 14. The lugs 29 and 30 project over the top and bottom edges of the bracket 16.

The binder member is secured in position for the purpose of maintaining the teeth 20 in engagement with certain of the teeth 15 of the flanges 13 and 14 through the medium of a pair of clamping screws 33, one of which extends through an opening 21 and has threaded engagement with the wall of the opening 31, and the other of which extends through the other opening 21 and has threaded engagement with the wall of the opening 32. When the binder member is secured in position by the clamping screws 33, the teeth 20 are held in engagement with certain of the teeth 15 and which maintain the supporting bracket in the position to which it was adjusted.

To release the seat supporting bracket, the lower clamping screw 33 is loosened freely and the upper one given a few turns, after which the bracket can be lowered and raised on the hinge principle, a slight raise of the entire bracket and it moves freely. Drop the entire bracket and it locks automatically.

It is thought that the many advantages of a combined connecting and adjusting means, in accordance with this invention, for a seat unit or structure, can be readily understood, and although the preferred embodiment of the invention is as illustrated and described,

yet it is to be understood that changes in the details of construction can be had which fall within the scope of the invention as claimed.

5. What we claim is:—

1. An article of furniture for the purpose set forth comprising a pedestal provided at its front with a pair of spaced racks and a pocket rearwardly of the racks, an adjustable seat supporting bracket grooved to overlap said racks, the walls of said groove provided with two spaced sets of teeth engaging with said racks for supporting the bracket in adjusted position, a binder member 15 mounted in said pocket, extending between said racks and sets of teeth and overlapping the top edge of said bracket, and adjustable clamping elements extending through said bracket and engaging said member for 20 clamping it within the pocket and to said bracket.

2. An article of furniture for the purpose set forth comprising a pedestal provided at its front with a pair of oppositely extending, vertically disposed, forwardly projecting spaced angle-shaped flanges providing in connection with the pedestal a pocket, the forward portion of each of said flanges gradually increasing in thickness from the top 30 to the lower end thereof and having its outer face toothed to provide a rack, an adjustable seat supporting bracket grooved to overlap said racks, the walls of said groove provided with two spaced sets of teeth engaging in the racks to support the bracket in adjusted position, a binder member slidably mounted in said pocket and projecting forwardly between said flanges and sets of teeth and having its top overlapping the 35 top edge of said bracket, and a plurality of adjustable clamping elements extending through the bracket and engaging said mem-

ber for holding it in binding position with respect to said flanges and brackets.

3. An article of furniture for the purpose 45 set forth comprising a pedestal provided at its front with a pair of spaced racks positioned forwardly of said front, an adjustable seat supporting bracket having its rear face in toothed engagement with said racks, a 50 binder element slidably mounted in the pedestal extending between said racks and having its top formed with a forwardly projecting angle-shape lug overlapping the top edge of said bracket, and adjustable means 55 carried by the bracket for securing the binder member in binding engagement with respect to the pedestal and bracket.

4. An article of furniture for the purpose set forth comprising a pedestal provided at 60 its front with a pair of spaced racks and a pocket, an adjustable seat supporting bracket having toothed engagement at its rear in proximity to and at each side of its vertical median with said racks, a binder element 65 slidably mounted in said pocket extending between said racks and engaging the rear of said bracket at the vertical median of the latter, adjustable, superposed clamping elements extending through said bracket at the 70 vertical median thereof and engaging in the binder element to secure it from movement for maintaining the bracket in adjusted position, said bracket provided with a notch in its top edge and in its bottom edge at the 75 vertical median thereof, and said binder element formed at its top and bottom with angularly disposed means extending through said notches.

In testimony whereof, we affix our signatures hereto.

WILLIAM R. BRENNAN.

WILLIAM J. BARGEN.
